UNITED STATES PATENT OFFICE.

GEORGE C. THOMPSON, OF EAST LIVERPOOL, OHIO, ASSIGNOR TO THE C. C. THOMPSON POTTERY CO., OF EAST LIVERPOOL, OHIO.

DESIGN FOR A SUGAR BOWL OR SIMILAR ARTICLE.

Application filed May 6, 1926. Serial No. 17,588. Term of patent 7 years.

To all whom it may concern:

Be it known that I, GEORGE C. THOMPSON, a citizen of the United States, residing at East Liverpool, in the county of Columbiana and State of Ohio, have invented a new, original, and ornamental Design for a Sugar Bowl or Similar Article, of which the following is a specification, reference being had therein to the accompanying drawings.

The predominant features of the design are the flat faces of the dish arranged at angles to one another, together with the flat faces of the lower lid portion and the flat

faces of the raised portion of the lid, all of which are arranged at angles to one another. The angular effect is also carried out in the handle of the article.

In the drawings:

Figure 1 is a view in side elevation of the article, showing my new design.

Figure 2 is a top plan view thereof.

I claim:

The ornamental design for a sugar bowl or similar article, as shown and described.

In testimony whereof, I hereunto affix my signature.

GEORGE C. THOMPSON.
